UNITED STATES PATENT OFFICE.

JOHANN GATZWEILER, OF LEIPZIG-GOHLIS, GERMANY, ASSIGNOR TO ADOLE BLEICHERT & COMPANY, OF LEIPZIG-GOHLIS, GERMANY.

AERIAL ROPEWAY.

Application filed July 2, 1924. Serial No. 723,657.

To all whom it may concern:

Be it known that I, JOHANN GATZWEILER, a citizen of the German Republic, residing at Leipzig-Gohlis, Leipzig, Germany, have 5 invented certain new and useful Improvements in Aerial Ropeways, of which the following is a specification.

My invention relates to aerial ropeways and it has particular relation to apparatus 10 of the character designated embodying carrying ropes and a traction rope, that is, a rope or ropes on which the load is carried and another rope attached to the loaded vehicle and movable to propel said load 15 along the carrying rope, which latter is, of course, stationary.

On ropeways with which I am familiar and embodying a stationary carrying rope and a moving traction rope, the latter will 20 take, in consequence of its longitudinal tension, a portion of the load between the supporting points when the sag of the traction rope is less than that of the carrying rope. At the rope supporting points, however, 25 where the traction rope is carried by rollers which are fitted either below the car or loaded vehicle, or directly under the traction rope clip, the traction rope will be lifted from its supporting rollers by reason 30 of the clip interposing between said rollers and the rope. This action results in the carrying rope being loaded with the dead weight of the load usually borne by the carrying rope. The load on the carrying 35 ropes at the load supporting points which results from this action even exceeds the weight of the loaded car, this following because the traction rope at this point bears no portion of the load, and as a matter of 40 fact imposes, on the carrying rope, as added weight, the load of the traction rope itself.

It is, therefore, obvious that at the supporting points the carrying rope is subjected to a markedly higher stress than it is 45 at any point between the supports. The rope wears out quite quickly at the supporting points and the effective life of the rope as a whole is thereby considerably shortened, since the intermediate elements 50 are generally too short to be economically utilized.

My invention, therefore, has for its principal object the provision of an improved aerial system whereby the lifting of the

traveling traction rope from its supporting 55 rollers will be prevented, so that the traction rope, even at these points, will be caused to bear a share of the load. The carrying rope will not, therefore, be subjected to the above-explained higher stresses at the supporting points, whereas a marked increase 60 in the life of the carrying rope will be secured. Moreover, with the assurance that the traction rope will bear its proper share of the load weight throughout its length, a 65 suitable tension can be selected for said traction rope whereby the maximum balanced portion of the weight of the load will be borne by said traction rope between the 70 points of support.

In order to attain the above object, I provide a special connection between the traction rope clips or traction rope carrying rollers and their supports. As will hereafter be more fully pointed out, the reciprocal shifting between the traction rope carrying rollers and the clips is arranged to take place in the vertical plane in which the traction rope is located, and a shifting 75 part is guided at right angles to the traveling rope. The result of this arrangement is that there will be no lateral shifting of the traction rope when the traction rope clip passes over the rope carrying rollers, and, therefore, the traction rope will not have 80 the tendency to fall from the rope roller.

Again, I arrange the traction rope clip so that it has a certain amount of play in its upward and downward movements between shift stops, whereby a desirable partial 85 loading of the traction rope and a corresponding relief of the carrying rope will result. The same result is attained in a given degree on reciprocally shifting traction rope carrying rollers and clips by providing in 90 addition to the traction rope, a load on the shifting part which will counteract the reciprocal shifting. This load will alter as soon as the detent alluded to comes into action.

My invention will be better understood by reference to the accompanying drawing, in which:

Figure 1 is an elevational, sectional view taken on the line A—B of

Fig. 2, which latter is a side elevational view showing the load mechanism fitted to the carrying and traction ropes;

100

105

Fig. 3 is a plan view of a portion of the apparatus shown in Fig. 2;

Fig. 4 is an elevational, sectional view similar to Fig. 1, but illustrating the manner in which my device will negotiate curves;

Fig. 4^A is a simplified diagrammatic showing of the manner in which the stresses in my system are distributed and balanced;

Fig. 5 is an elevational, sectional view of a modification of the device shown in Figs. 1 to 4 inclusive;

Fig. 6 is a fragmentary elevational, sectional view of another modification;

Fig. 7 is a side elevational view of one form which my invention contemplates;

Fig. 8 is a side elevational view of another form; and

Fig. 9 is a plan view of the device shown in Fig. 8.

Referring now more particularly to the device illustrated in Figs. 1 to 4, running wheels 1-1 are mounted on a carriage frame 2. One arm 3 of a pliers-shaped traction rope clip is pivoted at 4 to oscillate in said frame 2, being supported in its lowermost position by a joint or abutment 5 on the carriage frame 2, and in its highest position by the abutment 6 on said frame.

Another arm 7 of said clip is pivoted to the frame 2 by a bolt 8, and at its other end carries a roller 9 which is movable in a horizontal slot of the slide-piece 10. The latter is fitted in guide grooves 11 (see Fig. 1) to permit vertical shifting in the carriage frame 2. This slide-piece 10 is connected to the load carrier proper 12 by a swivel connection 13. It is apparent, therefore, that when load is imposed on 12 it acts on the arm 7 of the clip through downward pressure on the slidable member 10 whereby the closing force is generated to grip the traction rope. A coupling roller 14 is provided at the lower portion of the load carriage, and the opening and closing of the clip arms may be accomplished through this latter, in a well known manner.

A traction rope supporting roller 15 is fitted in a supporting frame at regular points along the path of travel of said rope. The carrying rope 16 supports the rollers 1 and is, of course, stationary while said rollers roll therealong. A movable traction rope 17 is shown as being gripped by the arms 3 and 7 of the traction rope clip and passing over roller 15.

In order to explain the manner in which a definite portion of the load is borne by the traction rope 17, reference may be had to Fig. 4^A which is a simplified diagrammatic showing of the essential elements of my structure and the manner in which the stresses are distributed therein and borne by said traction and carrying ropes.

I have represented the center of gravity

of the entire load as lying on a vertical line S and, therefore, the weight of the load carrier and load is represented as G, which weight acts as shown by the arrow through the center of gravity. It will be remembered, moreover, that the weight-carrier 12 is slidably arranged in the carriage portion 2. This has been illustrated in the sketch by the arrows p-p which represent the torque stresses imposed on the carriage 2 when the weight G acts along the line S, by reason of this force G acting to the side of the slideway.

The traction rope clips are represented in the simplified view by one composite arm 3/7, which arm is supported at its outer end by the traction rope 17, the force at the point being represented by the arrow A, which acts about the pivot point 4, at which point the arms of the rope clip are supported on the carriage 2.

The supporting force of the carrying rope 16 is indicated by the arrow C, representing the upward force exerted by said carrying rope.

It will be seen from a consideration of this simplified drawing that the entire load is transferred to the carriage 2 and the carrying rope 16, through the roller on the arms 3/7 and the support of these arms at 4, and, therefore, the stress represented by the arrow B is equal to G-A.

In order now to prove that the traction rope will bear, by reason of the novel arrangement of the elements heretofore described, a proportion of the load, the following equations may be set down, remembering that the sum of the moments about a given point must be equal to zero, and also noting that the distance between the traction rope and the point 4 is designated as b, and that the distance between the point where load carrier 12 is connected to arm 3/7 and point is designated as a. Therefore,

$$A = G \frac{a}{b}$$

Now the entire weight of the car consists of the weight of the carriage body itself, which is represented by g acting at the point shown, plus the load weight G. Moreover, a balanced condition must be realized between the weights G and g and the supporting ropes exerting the upward forces A and C. Therefore:

$$G + g = A + C$$

$$\therefore C = G + g - A$$

$$\therefore C = G + g - G \frac{a}{b}$$

$$\therefore C = g + G \left(1 - \frac{a}{b}\right)$$

It follows, therefore, that the actual weight imposed on the carrying rope will be

less than the weight which would otherwise be imposed thereupon; that is, the parenthesis $(1 - \frac{a}{b})$ will always, under practical 5 conditions, be less than 1, and it is apparent that any desired degree of imposition of weight upon the traction rope may be provided for. Moreover, since the center of gravity of the entire device is considerably 10 below the supporting points A and C, this point can freely deflect and automatic adjustment will always take place.

In the type of apparatus above described, I select a relative position of the traction 15 rope in such manner that the clip will guide the traction rope on the opposite side of the load carriage and far enough above the rope level of the traction so that rollers 18 (see Fig. 4) arranged in a horizontal plane 20 may pass between the carrier and the rope clip. A thrust roller 19 is fitted on the traction rope clip and arranged to contact with a guide 20. This particular showing illustrates the ease with which weight carriers 25 may traverse curves when the same are supported by mechanism arranged in accordance with my invention.

When the opening in the traction rope clip is towards the bottom, the lower ends 30 of the clip jaws may be made very short and arranged to correspond with the peripheral groove in the traction rope rollers. This not only promotes a smooth passage 35 of the clip over the rollers, but at the same time reduces to a minimum the shifting of the clip arm.

In Fig. 5 I have illustrated a device which is much the same as those shown in Figs. 1 and 4, with the exception that the traction 40 rope in this system is disposed, at the supporting points, slightly above the carrying rope, or approximately at the top level of the track. I find that this system is of special advantage in that no lateral shift 45 of the clip will occur when the vehicle or weight carrier oscillates transversely of the direction of travel, whereby the accurate introduction of the traction rope into the clip, when coupling, is insured.

The device illustrated in Fig. 6 shows a 50 rope clip of simplest type which is tightened by means of a screw nut. In this figure one jaw 21 of the rope clip is secured on a slide 22, which latter is arranged to ship vertically in the carriage 2, whereas the other jaw 23 is drawn through the nut 24 by means of its bolt, which latter is furnished with a thread. A lever 25 with a 55 closing weight 26 causes movement of the screw. A spring 27 gives a counter loading effect when the rope clip tends to shift. It will be noted that the load carrier 12 is carried directly on the carriage casing 2 by the bolt 13, as before.

In Fig. 7 a type is represented on which

the reciprocal shifting of traction rope carrying rollers and clips is transmitted to the carrying rollers. Two traction rope carrying rollers 28 are fitted to oscillate around the bolts 29 on the support by means 70 of the lever of a balance 30. Each of these is loaded by the other to counteract shifting away from the traction rope clip.

In Figs. 8 and 9 a device for a similar purpose is shown with only one traction rope 75 carrying roller 31. The bearings 32 of the roller are fitted to shift vertically on two plate-springs 33. The bending resistance of the springs leads the roller to counteract the pressure of the traction rope clip. 80

The rope clips which are fitted to shift towards the traction rope carrying rollers in the plane in which the traction rope is located and at right angles to the traveling track, can also be utilized to relieve the carrying rope from the additional load from the traction rope only, when relieved of the forces counteracting the reciprocal shifting movement, without a part of the vehicle load being transmitted to the traction rope. 90

While I have described a plurality of embodiments of my invention, it is apparent that many other modifications thereof may occur to those skilled in the art which will not depart from my invention, and I desire the latter, therefore, to be limited only by the scope of the appended claims or by the prior art.

Having described my invention what I claim as new and desire to secure by Letters 100 Patent of the United States is:

1. In combination in an aerial ropeway embodying a carrying rope and a traction rope, a load carriage member, and means connecting said carriage to said ropes to insure that both of the latter are loaded at 105 all times.

2. In combination in an aerial ropeway embodying a carrying rope and a traction rope, supporting members for said traction rope, load carriage means, and clip means so connecting said carriage to said traction rope that the latter bears a portion of the load when passing over said members. 110

3. In combination in an aerial ropeway embodying a carrying rope and a traction rope, supporting members for said traction rope, load carriage means, and vertically reciprocal clip means so connecting said carriage to said traction rope that the latter bears a portion of the load when passing over said members. 115

4. In combination in an aerial ropeway embodying a carrying rope, a traction rope, and spaced supports for the same, a carriage member, a load supporting member connected to said carriage member and shiftable vertically with respect thereto and a traction rope clip secured to said load supporting member. 125

5. In combination in an aerial ropeway embodying a carrying rope, a traction rope, and spaced supports for the same, a load supporting member, a traction rope clip secured to said member, and means permitting the shifting of said clip in the vertical plane of said traction rope and at right angles to the path of travel. 55
6. In combination in an aerial ropeway embodying a carrying rope, a traction rope, and spaced supports for the same, a load supporting member, a carriage having guides therein in which said load supporting member may vertically shift, and a traction rope clip secured to said load supporting member. 60
7. In combination in an aerial ropeway embodying a carrying rope, a traction rope, a load supporting member, a carriage and a traction rope clip comprising two arms, one of the latter being pivoted on said carriage and the other adapted for vertical reciprocation with respect to said carriage. 65
8. In combination in an aerial ropeway embodying a carrying rope, a traction rope, a load supporting member, a carriage and a traction rope clip comprising two arms, one of the latter being pivoted on said carriage, a roller secured to said load supporting member and the end of the other of said arms being secured to said roller whereby vertical reciprocation of said arm with respect to said carriage may take place. 70
9. In combination in an aerial ropeway embodying a carrying rope, a traction rope, a load supporting member, a carriage and a traction rope clip comprising two arms, one of the latter being pivoted on said carriage, a roller secured to said load supporting member and the end of the other of said arms being secured to said roller, and means comprising guides in said carriage whereby said roller may shift in the vertical plane of said traction rope and at right angles to the path of travel. 75
10. In combination in an aerial ropeway embodying a carrying rope, a traction rope, a load supporting member, a carriage and a traction rope clip comprising two arms, one of the latter being pivoted on said carriage and the other adapted for vertical reciprocation with respect to said carriage, and means for limiting the upper and lower movements of said last named arm. 80
11. In combination in an aerial ropeway embodying a carrying rope, a traction rope, and spaced supports for the same, a traction rope clip adapted to shift in the vertical plane of the traction rope and at right angles to the path of travel, and means for imposing an additional load, in addition to the traction rope, on said clip to counteract the vertical shifting of said clip at said supports. 85
12. In combination in an aerial ropeway embodying a carrying rope, a traction rope, and spaced supports for the same, a traction rope clip adapted to shift in the vertical plane of the traction rope and at right angles to the path of travel, said clip comprising jaws opening downwardly, and a load supporting member, said clip being arranged on the side of the carrying rope opposite said load supporting member and below the level of said carrying rope support whereby the negotiation of curves in a horizontal plane is possible. 90
13. In combination in an aerial ropeway embodying a carrying rope, a traction rope, and spaced supports for the same, a traction rope clip adapted to shift in the vertical plane of the traction rope and at right angles to the path of travel, said clip comprising jaws opening downwardly, a load supporting member, said clip being arranged on the side of the carrying rope opposite the said load supporting member and below the level of said carrying rope support whereby the negotiation of curves in a horizontal plane is possible, a thrust roller on said clip, and a guide on the support at said curve 95 against which said thrust roller bears.
14. In combination in an aerial ropeway embodying a carrying rope and a traction rope, a load carriage-member, a traction rope-supporting roller, means connecting said carriage to said ropes to insure that both of the latter are loaded at all times, said means comprising a traction rope clip adapted to shift in the vertical plane of the traction rope and at right angles to the path of travel, said clip opening downwardly and comprising relatively short arms which latter are shaped to conform to the contour of the traction rope-carrying roller, whereby the lift of said clip is minimized. 100
- In testimony whereof I affix my signature. 105

JOHANN GATZWEILER.

Certificate of Correction. *

It is hereby certified that in Letters Patent No. 1,571,520, granted February 2, 1926, upon the application of Johann Gatzweiler, of Leipzig-Gohlis, Germany, for an improvement in "Aerial Ropeways," errors appear in the printed specification requiring correction as follows: Page 2, line 109, after the word "point" insert the numeral 4; page 3, line 55, for the word "ship" read *shift*; page 4, line 4, claim 5, for the misspelled word "supporing" read *supporting*; and that the said Letters Patent should be read with these corrections therein that the same may conform to the record of the case in the Patent Office.

Signed and sealed this 13th day of April, A. D. 1926.

[SEAL.]

M. J. MOORE,
Acting Commissioner of Patents.
